(57) **CLAIM**

The ornamental design for a combined container and dispenser as shown and described.

DESCRIPTION

FIG. 1 is a perspective view of a combined container and dispenser, showing a first embodiment of our new design with a top cover in an open position;

FIG. 2 is a perspective view thereof, illustrated with the top cover in a closed position;

FIG. 3 is a front elevational view of FIG. 2;

FIG. 4 is a rear elevational view of FIG. 2;

FIG. 5 is a left-side elevational view of FIG. 2;

FIG. 6 is a right-side elevational view of FIG. 2;

FIG. 7 is a top plan view of FIG. 2;

FIG. 8 is a bottom plan view of FIG. 2;

FIG. 9 is a perspective view of a second embodiment of our new design with the top cover in the open position;

FIG. 10 is a perspective view thereof, illustrated with the top cover in the closed position;

FIG. 11 is a front elevational view of FIG. 10;

FIG. 12 is a rear elevational view of FIG. 10;

FIG. 13 is a left-side elevational view of FIG. 10, the right-side elevational view being a mirror image thereof;

FIG. 14 is a top plan view of FIG. 10; and,

FIG. 15 is a bottom plan view of FIG. 10.

The broken lines in the figures depict portions of the combined container and dispenser that form no part of the claimed design.

1 Claim, 11 Drawing Sheets
